DESIGN FOR A GLIDING SETTEE

Robert M. Rink, Goshen, Ind., assignor to
Goshen Manufacturing Company, Goshen, Ind.

Application February 21, 1940, Serial No. 90,408

Term of patent 7 years

To all whom it may concern:

Be it known that I, Robert M. Rink, a citizen of the United States, residing at Goshen, in the county of Elkhart, State of Indiana, have invented a new, original, and ornamental Design for Gliding Settees, of which the following is a specification, reference being had to the accompanying drawing, forming part thereof.

The figure is a side perspective view of a gliding settee embodying my new design.

I claim:

The ornamental design for a gliding settee, as shown.

ROBERT M. RINK.
